UNITED STATES PATENT OFFICE.

ROBERT GEO. MARSH, OF DETROIT, MICHIGAN, ASSIGNOR TO THE MARSH AUTOMATIC SODA FOUNTAIN CO., OF DETROIT, MICHIGAN, A CORPORATION OF MICHIGAN.

LIQUID-DISPENSING APPARATUS.

1,169,337.

Specification of Letters Patent. Patented Jan. 25, 1916.

Application filed October 23, 1911. Serial No. 656,110.

To all whom it may concern:

Be it known that I, ROBERT GEO. MARSH, a citizen of the United States of America, residing at Detroit, in the county of Wayne 5 and State of Michigan, have invented certain new and useful Improvements in Liquid-Dispensing Apparatus, of which the following is a specification, reference being had therein to the accompanying drawings.

10 This invention relates to an apparatus for delivering measured quantities of fluid and more particularly to such an apparatus suitable for soda water fountains and other beverage dispensing devices, and its object 15 is to provide a simple and convenient device having certain new and useful features in the construction and arrangement of its parts, the invention consisting in the matters hereinafter set forth and more particularly 20 pointed out in the claims, reference being had to the accompanying drawings in which—

Figure 1 is a side elevation of an apparatus embodying the invention and showing 25 the same embodied in a soda fountain with adjacent parts of the fountain in section; Fig. 2 is an enlarged sectional detail of one of the valves; Fig. 3 a cross section of the same on the line $\alpha-\alpha$ of Fig. 2; Fig. 4 is a 30 vertical section through the apparatus detached from the fountain; Fig. 5, a cross section of the same on the line $y-y$ of Fig. 4; Fig. 6, a section on the line $z-z$ of Fig. 5; Fig. 7 is a plan view of Fig. 4; Fig. 8 is a 35 sectional detail showing a modified construction; and Fig. 9, a side elevation of Fig. 8 with parts in section.

For convenience of illustration, the invention is shown in Fig. 1 as applied to a soda 40 water fountain and in this structure 1 represents a table top or counter to the underside of which a suitable cast metal frame 2 is secured having two valve cylinders 3 and 4 formed integral therewith and connected 45 with each other by a bridge bar 5. Each cylinder is bored to receive a piston valve 6 which fits therein and at its inner end each cylinder bore is enlarged to form a chamber 7 having an inlet and an outlet port. The 50 inlet port 8 of the cylinder 3 is located at the axis of its inner end and a pipe 9 leading to this port is attached to cooling pipes 10 located in a tank 11 which may be filled with

ice. Leading from the opposite end of the cooling pipes is a pipe 12 which is connected 55 to a tank 13 containing carbonated water or similar fluid under pressure. The pressure in the tank 13 thus forces the water up through the pipes into the valve cylinder 3 under control of the piston 6 which is provided with a block 14 of rubber or other flexible material to seat upon the inner end of the cylinder and close the inlet port 8.

The outlet port 15 of the cylinder 3 is formed by a passage 16 which cuts into the 65 top of the chamber 7 and extends through the bridge bar 5, opening at its opposite end into the chamber 7 of the cylinder 4 through the inlet port 17 of said cylinder. In the rear end of this passage 16 is secured a pipe 70 18 leading downward to a small measuring receptacle 19 located within the ice tank 11 where its contents will be kept cool. An axial outlet port 20 in the end of the cylinder 4 connects with a pipe 21 leading into 75 a mixing nozzle 22 which is formed with a chamber 23 having a discharge opening at its lower end. The end of the pipe 21 is provided with a downturned end forming a discharge nozzle 24 for directing a stream 80 through the opening in the mixing nozzle, and the pipe is also provided with a small discharge opening 25 near the upper end of the chamber 23 to cause the carbonated water to foam in said chamber. 85

Each of the valve pistons 6 is guided in its cylinder to move longitudinally therein toward and from the seat upon the end of the cylinder, by guides or keys 26 which prevent the piston from turning, and to move each piston, each is formed with an axial screwthreaded opening to receive the inner screwthreaded end 27 of a rod 28 which extends outward through a packing nut 29 screwed into the end of the cylinder 95 and is provided with a gear 30 on its outer end. Said rod is formed with a flange 31 to engage a groove in the cylinder at the inner end of the stuffing box or nut 29 and prevent any longitudinal movement of the 100 rod through the box. By its screw-threaded engagement with the piston, said rod thus moves the valve toward or from its seat when the rod is turned by means of the gear 30. 105

A tubular operating member 32 is mount-

ed in suitable bearings 33 and 34 on the frame 2 to move freely therein and this tube is provided with a longitudinal slot 35 in its lower side into which the gears 30 project. A rack bar 36 is adjustably held within the tube in a position to be engaged by the gears when the tube is moved longitudinally through the bearings, and this rack is so located and of such a length that 10 said gears will be turned successively by it in the proper direction and far enough to actuate the valves the proper distance and in the desired direction. By means of a small rod 37 secured to one end of the rack 15 bar, said bar may be moved longitudinally in the tube to adjust it relatively to the gears and the rod is actuated by a rotatable member 38 secured in the forward end of the tube against longitudinal movement 20 therein but free to turn and having a screw-threaded axial opening to receive the screw-threaded end of the rod. The length of the slot 35 is such that when the tube is moved to the limit of its movement in either 25 direction, one gear will be engaged by one end of said slot and the other gear will be in engagement with the rack so that both gears will be held from turning with the teeth on the gear which is out of engagement 30 with the rack, in position to reengage the teeth on said rack. By adjusting the rack bar longitudinally in the tube it will actuate the gears to close the valves more or less tightly.

35 When the invention is embodied in a soda fountain as shown in Fig. 1, means are provided for delivering measured quantities of flavoring or syrup with the soda water, comprising an inverted cup 39 secured upon the 40 lower end of a tube 40 which is secured at its upper end within a suitable bearing bracket 41 extending downward from the frame 2. The tube extends downward within a suitable glass jar 42 or other container 45 for syrup with the cup near the bottom of the container and leading from the upper end of said tube in a small pipe 43 which extends forwardly into the mixing nozzle 22 and opens into the chamber 23 thereof to 50 deliver syrup thereto from the tube.

To force measured quantities of syrup up through the tube, a rod 44 extends through a stuffing box 45 at the upper end of the tube and downward in the axis of said tube 40 to the cup 39 where it is provided with a valve comprising a disk 46 upon the lower end of the rod which disk is of considerably less diameter than the internal diameter of the cup to permit the syrup to flow into the cup around the edge of the disk. Fitting within the cup and loosely mounted upon the rod above the disk, is a valve disk or member 47 having openings for the passage of the syrup therethrough when the valve is 55 lifted from the surface of the disk 46 which

forms a seat therefor. When said valve member is in contact with the disk, the space between the edge of the disk and the cup is closed thereby and the openings through the member are closed by the disk. A collar 73 48 on the rod is provided to limit the movement of the valve member 47 upon the rod. Immediately above the upper end of the cup 39 there is formed a chamber 49 for a downwardly seating valve 50 adapted to 75 slide on the rod 44 toward and from a seat member 51 screwed into the lower end of the chamber and formed with ports which are closed by the valve. This valve rises and permits the syrup to pass upward into 80 the tube from the cup when the rod is actuated to lift the valve 47 and force the syrup upward. Upon the downstroke of the rod, and lowering of said valve 47, said valve 50 closes and holds the syrup in the tube and 85 at the same time the valve 47 is lifted from its seat disk 46 by the downward movement of the rod and the syrup is permitted to pass into the cup around the edge of the disk and through the openings in the valve. 90 Measured quantities of syrup equal to the capacity of the cup, are therefore forced upward through the tubes 40 and 43 into the mixing chamber 23 of the nozzle upon each actuation of the valve 47.

Upon the upper end of the rod 44 is a rack-bar 52 to engage a pinion 53 upon one end of a short horizontal transverse shaft 54 mounted in a bearing formed integral with the bridge bar 5 and upon the opposite end of said shaft is a gear 55 adapted to be engaged by a rack bar 56 similar to the rack bar 36 and mounted within a slotted actuating tube 57 similar to the tube 32, which tube 57 is mounted in horizontal bearings 58 100 and 59 upon the frame 2 at the side thereof opposite that at which the tube 32 is supported. Each of the actuating tubes 32 and 57 is provided with a head or knob 60 on its forward end by means of which it may be 105 actuated by the operator and a detachable handle bar 61 is provided for connecting the tubes at their forward ends so that they may be simultaneously operated.

When the operating tubes 32 and 57 are in the position shown in Fig. 6 the valve in the cylinder 3 is held open and the valve in the cylinder 4 held closed by the engagement of the rack 36 and the end of the slot with the gears for operating said valves, respectively, the rod 28 for operating the said valve in cylinder 3 being provided with a left hand screw-thread for moving the piston valve. The full pressure of carbonated water is thus free to enter the measuring receptacle 19 but is prevented from escaping into the mixing nozzle 22 by the valve in cylinder 4. At the same time the valve 47 is in lowered position and the cup 39 is full 110 of syrup so that upon forward actuation of 115

the operating tubes by the handle 61, the said valve will be lifted in the cup, forcing its contents up into the chamber 23 of the mixing nozzle. Simultaneously with the discharge of the syrup into the mixing chamber, the valve of cylinder 3 is closed and the valve of cylinder 4 opened by said movement of their operating tube, thus closing off the supply from the tank 13 and allowing the carbonated water which is in the measuring receptacle under pressure to escape into the mixing chamber of the nozzle where it is mixed with the syrup and discharged from the nozzle in condition for use. As shown in dotted lines in Fig. 1, the pipe 18 is extended downward within the receptacle to near the bottom thereof so that the gases trapped in the upper part of said receptacle will force the water in the receptacle out through the tube when the outlet valve in the casing 4 is opened, permitting said gases to expand. A measured quantity of soda water and syrup is thus mixed and discharged by a single movement of the operating tubes, and a measured quantity of either soda water or syrup may be delivered by disconnecting the handle 61 from one of said tubes and moving one of the tubes only.

It is obvious that the invention may be embodied in liquid dispensing devices other than that illustrated in Figs. 1 to 7 inclusive, and the modified construction shown in Figs. 8 and 9 is an example of such a device, 62 indicating a suitable liquid receptacle having a downwardly extending discharge passage communicating with the inlet port 63 of a valve cylinder 64. A second valve cylinder 65 is provided below the cylinder 64 and a measuring receptacle 66 is located between said cylinders to receive liquid admitted through the outlet port 67 of said cylinder 64. The liquid in the measuring chamber is discharged through an inlet port 68 and an outlet port 69 in the cylinder 65, and the ports 63 and 69 are controlled by piston valves 6 in the cylinders, constructed and operated in the same manner as the piston valves shown in Figs. 1 to 7. A vent tube 77, extends upward from the chamber 66 into the receptacle 62 so that the fluid will flow by gravity into the chamber. The gears 30 for actuating these valves are spaced apart, and an operating tube 70 having slots in its upper and lower sides to receive the gears, is supported in a horizontal position to slide freely through a bearing 71. A rack bar 72 is provided in the tube to engage the gear at the upper side of the tube and a rack bar 73 to engage the lower gear. These bars may be moved longitudinally in the tube by rods 74 secured to their ends and having screw-threaded engagement with adjusting members 38 similar to the members for adjusting the rack bar 36. Projections 75 on the

bar 72 are provided to engage the gears and hold them in the position to which they are turned.

A forward movement of the operating tube from the position shown in Fig. 9 will first close the valve in cylinder 64 and then open the valve in cylinder 65, allowing the liquid trapped in the measuring receptacle to flow out, and an opposite movement of the operating tube will first close the lower valve 75 and then open the upper, to admit the liquid into the measuring chamber.

Having thus fully described my invention what I claim is:—

1. In a liquid dispensing apparatus, the combination with a liquid supply receptacle, a measuring receptacle, a valve for controlling the flow of liquid from one to the other of said receptacles, a discharge nozzle, and a valve controlling the flow of fluid 85 from the measuring receptacle into the nozzle; of a single longitudinally reciprocable member adapted to open one valve and to close the other and vice versa whenever shifted from one limit of its movement to the other.

2. In a liquid dispensing apparatus, the combination with a liquid supply receptacle, a measuring receptacle, a valve for controlling the flow of liquid from one to the other of said receptacles, a discharge nozzle, and a valve controlling the flow of liquid from the measuring receptacle into the nozzle; of gears connected to said valve to actuate the same, and a reciprocable rack bar 100 to successively engage and turn said gears in the same direction to alternately open and close said valve.

3. In a liquid dispensing apparatus, the combination with a liquid supply receptacle, a measuring receptacle, a valve for controlling the flow of liquid from one to the other of said receptacles, a discharge nozzle and a valve controlling the flow of liquid from the measuring receptacle into the nozzle, of gears each connected to a valve and adapted to open and close the same, and a reciprocable rack bar adapted to engage first one gear to open one valve and then the other gear to close the other valve when moved in one direction, and open the last mentioned valve and close the first mentioned valve when moved in an opposite direction, between its limits of motion.

4. In a liquid dispensing apparatus, the combination with a liquid supply receptacle, a measuring receptacle, a valve for controlling the flow of liquid from one to the other of said receptacles, a discharge nozzle 125 and a valve controlling the flow of liquid from the measuring receptacle into the nozzle; of gears each connected to a valve to open and close the same, and a reciprocable member having a rack bar adapted to successively engage said gears to open one 130

valve and then close the other when moved from one limit of motion to the other and vice versa and provided with stops to engage and hold the gears at each end of its 5 reciprocation.

5. In a liquid dispensing apparatus, the combination with a liquid supply receptacle, a measuring receptacle, a valve for controlling the flow of liquid from one to the 10 other of said receptacles, a discharge nozzle, and a valve controlling the flow of liquid from the measuring receptacle into the nozzle; of gears connected to said valves to actuate the same, a reciprocable slotted operating tube, a rack bar within said tube adapted to engage said gears, a rod secured to said rack bar and extending to one end of the tube, and means engaging the end of the rod to move the same and actuate the 15 rack bar in the tube longitudinally thereof.

6. In a liquid dispensing apparatus, the combination with a liquid supply receptacle, and a measuring receptacle; of a frame formed with cylinders, and a passage connecting said cylinders, said supply receptacle being connected to one of said cylinders to supply fluid thereto and said measuring receptacle being connected to said passage to receive liquid from said cylinder 20 and discharge it into the other cylinder, valve members in said cylinders to control the flow of liquid therethrough, means for operating said valves and a nozzle connected to one of said cylinders to receive fluid 25 therefrom.

7. In a liquid dispensing apparatus, the combination with a liquid supply receptacle, a measuring receptacle, and conduits connecting said receptacles; of a valve controlling said conduits and a valve controlling the outlet from the measuring receptacle, each of said valves comprising a cylinder having an inlet and an outlet port, a valve piston reciprocable within said cylinder to open and close one of the ports, and a rod to actuate said piston, a gear on the outer end of each rod of each valve, and means to successively engage and turn said gears in timed relation to each other.

50 8. In a liquid dispensing apparatus, the combination with a liquid supply receptacle, a measuring receptacle, and conduits connecting said receptacles; of a valve controlling said conduits and a valve controlling the outlet from the measuring receptacle, each of said valves comprising a cylinder having an inlet and an outlet port, a valve piston reciprocable within said cylinder to open and close one of the ports, a 55 rod having screwthreaded engagement with the piston to move the same longitudinally when the rod is turned, gears on the outer 60

ends of the rods, a reciprocable member, and a rack bar carried by said member to successively engage and actuate the gears. 65

9. In a liquid dispensing apparatus, the combination of a measuring receptacle, a mixing nozzle, a valve controlling the flow from the measuring receptacle to the nozzle, a measuring cup adapted to discharge into 70 said nozzle, means for forcing liquid from the cup into the nozzle, members for actuating said valve and means, and means for detachably connecting said members whereby they may be simultaneously or independently operated.

10. In a liquid dispensing apparatus, the combination of a measuring receptacle, a mixing nozzle, a valve controlling the flow from the measuring receptacle to the nozzle, a measuring cup adapted to discharge into 75 said nozzle, means within the cup to force liquid from the cup into the nozzle, a reciprocable member for actuating the means within the cup, a reciprocable member for actuating the valve, and means for connecting and disconnecting said reciprocable members. 80

11. In a liquid dispensing apparatus, the combination of a nozzle, a measuring receptacle, a valve controlling the flow from the measuring receptacle to the nozzle, a gear for actuating said valve, a measuring cup adapted to discharge into said nozzle, means within the cup for forcing liquid 90 from the cup into the nozzle, a gear for actuating said means, a reciprocable member for actuating each gear, and a member adapted to be attached to said reciprocable members to cause the same to move together 95 and actuate the gears in timed relation to each other.

12. In a liquid dispensing apparatus, the combination of a measuring receptacle, a mixing nozzle, a valve controlling the flow 105 from the measuring receptacle to the nozzle, a gear for actuating said valve, a measuring cup adapted to discharge into said nozzle, means within the cup for forcing liquid from the cup into the nozzle, a gear 110 for actuating said means, longitudinally reciprocable members connected to move together, and rack bars carried by said reciprocable members and arranged to actuate one of the gears in advance of the other 115 to operate the valve and means within the cup in timed relation to each other.

In testimony whereof I affix my signature in presence of two witnesses.
